INVENTOR.
Charles Mehl

BY

Herbert S. Fairbanks

ATTORNEY.

UNITED STATES PATENT OFFICE

CHARLES MEHL, OF PHILADELPHIA, PENNSYLVANIA

DIVING TANK

Application filed August 28, 1931. Serial No. 559,867.

The object of this invention is to devise a novel diving tank which is adapted for one man operation, and in which the tank is constructed in such a manner that the moving parts are effectively sealed. The tank is provided with a series of observation windows directed in different directions so that the operator can always have within his vision the object which he is seeking, even though the tank is revolving.

A further object of the invention is to provide a novel construction and arrangement of grappling arms and novel means for controlling them from within the diving tank.

With the above and other objects in view as will hereinafter more clearly appear, my invention comprehends a novel diving tank.

It further comprehends a novel diving tank adapted for one man operation having a plurality of observation windows facing in different directions, and provided with a novel arrangement and construction of grappling arms and with novel means for controlling said arms.

It further comprehends a novel construction and arrangement of tank, and novel means for securing a cable thereto.

It further comprehends novel means for cushioning the tank when it reaches the bottom of the ocean bed or the bed of a water-way.

It further comprehends a novel construction and arrangement of a revolving seat for the operator.

Other novel features of construction will hereinafter fully appear in the detailed description and the appended claims.

For the purpose of illustrating the invention I have shown in the accompanying drawings a preferred embodiment of it which in practice will give satisfactory and reliable results. It is, however, to be understood that the various instrumentalities of which my invention consists can be variously arranged and organized, and the invention is not limited to the precise arrangement and organization of these instrumentalities as herein set forth.

Figure 1 is a side elevation, partly broken

away, of a diving tank embodying my invention.

Figure 2 is a section on line 2—2 of Figure 1.

Figure 3 is a sectional view of a portion 55 of a grappling arm and its controlling mechanism.

Figure 4 is a sectional view of the forward end of a grappling arm.

Figure 5 is a sectional view of the cover 60 showing the cable connection.

Figure 6 is a detailed view showing the arrangement of threads on the cover.

Figure 7 is a detailed view of a portion of 65 a wing, showing more clearly the hydraulic cushioning mechanism.

Similar numerals of reference indicate corresponding parts.

Referring to the drawings:

1 designates the casing of a diving tank 70 embodying my invention. The casing 1 is provided with a rounded bottom 2 and extending downward from the bottom are the wings 3 which are disposed at right angles to each other so that when the diving tank 75 settles on the bed of a water way the tank will stay in position without revolving. I also provide cushioning members 4 in the form of plungers mounted in the casings 5, and between the upper end of the plungers 80 and the upper walls of the casings are interposed springs 6, so that, when the tank strikes the bottom of the water way a mechanical cushion will be provided. Four of these cushioning plungers are provided in the 85 wings 3 circumferentially spaced around the bottom, and I also provide a centrally disposed cushioning plunger 7 which is constructed and operated in a similar manner to that of the plungers already described.

The upper end of the tank is provided with a removable cap or closure 8 having a downwardly projecting threaded flange 9, the threads of which are broken or intermittent, and the threaded wall 10 of the opening at the upper end of the tank is, in a similar manner, provided with intermittent or broken threads, so that a quick detachable closure is provided. It is thus unnecessary 100

to screw the closure into place but by giving it a partial turn it can be removed.

In order to lock the closure in its assembled position I provide the fastening devices 11, which, when screwed into the wall of the tank 1, prevent relative rotation of such closure and tank. The closure 8 is provided with a relief valve 12 controlling air communication between the atmosphere and the interior of the tank, so that the pressure can be balanced after the tank is raised from the water.

The upper end of the tank 1 is provided with an annular groove as shown at 13', into which extends an annular rib 14' on the bottom of the closure 8, and packing 15' is interposed between said rib and the bottom of the annular groove 13. I provide a series of observation windows in order that the operator may be able to look out of the tank in a number of different directions. The closure 8 is provided with four circumferential-ly spaced observation windows 13, which are sealed in position.

At the upper end of the tank, I also provide four observation windows 14 circumferentially spaced around the side wall, and directed upwardly at an angle. I also provide the observation windows 15 which are circumferentially spaced, four of them being employed, and these extend laterally from the side wall of the tank. Below the observation windows 15, I provide four downwardly projected observation windows 16, circumferentially disposed around the circumference of the tank. It will now be clear that I provide 16 non-breakable windows which enable the operator within the tank to see in any direction.

The cable 17 is connected with the closure 8 in a novel manner, and through this cable extends the telephone connection 18, so that the telephone connection is properly protected and no injury can occur to it unless the cable breaks. A fitting 19 is screwed into the upper end of the closure 8 and in the chamber of this fitting is tubular packing 20 in the form of reversely inclined cones which are compressed by means of a gland 21 against which bears a tubular closure 22, which is provided with a threaded extension of reduced diameter in threaded engagement with the fitting 19. The chamber of the fitting 19 at its lower end is cone shaped to conform to the contour of the packing, and the chamber of the gland 21 is also cone shaped to conform to the portion of the packing with which it contacts. The upper end of the closure 8 is provided with a cored space forming an annular channel 23 across which extends a solid rod 24 which is integral with the casting of which the closure 8 is composed. The cable 17 is wound around this rod 24 so that the strains of the cable are taken on this rod. The annular channel 23

communicates with the chamber 25, the wall of which is cone shaped and diverges downwardly in order to provide for the locking of the lower end of the cable. The strands of the cable at this point are divided and pressed outwardly, and the lower ends of the strands are wrapped around the rings 26. The space within this chamber 25 is then filled with molten metal so that the lower end of the cable is securely anchored to the closure 8. Beneath the terminal of the lower end of the cable the wall of the casing is threaded to receive a closure disc 27. This closure 27 has a contact member 28 in electrical connection with the cable 18, so that the telephone conductor 29 leading to the telephone 30 can be plugged in. 31 designates the oxygen breathing units, two of which are employed, which will supply sufficient oxygen under atmospheric pressure for a period of eight hours. The bottom of the tank has rising from it a standard 32 on which is mounted a revolving stool 33, having a seat for the operator, and this is preferably mounted on ball bearings 34.

Grappling mechanism

As before explained, I provide observation windows arranged in sets of four, and between two adjacent lower observation windows I provide a grappling device having its own individual control located within the tank in a position accessible to the operator. 35 designates a grappling arm, four of which are employed, and they are composed of several movably connected sections so that the position of the grapples or hooks 36 may be varied as desired. Each grappling arm is rotatably mounted.

37 designates a hand wheel fixed to the hub of a gear 38 mounted on a stud shaft 39 carried by the machine frame. The gear 38 meshes with a gear 40 fixed to a gear 41 which latter is mounted on a stud shaft 42. The gear 41 meshes with a gear 43 fixed to a reduced extension 44 of a grapple carrying member in the form of a slotted support 45. This reduced extension 44 extends through an opening in the side wall of the diving tank and carries a thrust bearing 46 which bears against the juxtaposed recessed wall of the tank and the inner enlarged end of the grapple arm support 45 with which cooperates a packing 48 which is retained in position by means of a gland 49. It will thus be seen that if the hand wheel 37 is revolved the grapple arm support 45 will also be revolved. 50 designates the first movable section of the grapple arm which is provided at its inner end with a bifurcated portion 51 which extends into the support 45 and is pivoted thereto by means of the pivoted members 52 which form trunnions. The movable section 50 at its outer end is bifurcated to receive the bi-

furcated end of the movable section 53 which is pivotally connected therewith as at 54.

The hooks 36 are pivotally supported at 55 in the bifurcated end of an apertured arm section 56. The inner ends of the hooks are pivotally connected to one end of the links 57, the opposite ends of which are pivotally connected to an arm 58 fixed to a rod 59. The outer end of the arm 53 is recessed to receive a ball bearing 60 which also bears against a shoulder on the arm 58 and this arm is rotatably mounted in the movable section 53 and is retained in place by means of a cap nut 61 which is screwed into the outer recessed end of the movable section 53. The rod 59 has adjustably mounted thereon a set collar 62 between which and a wall of the movable section 53 is interposed a spring 63. The rod 59 has connected with its rear end a cable 64 which extends rearwardly and is connected to a controlling rod 65 which is provided with a grasping handle 66. The cable 64 passes through a bearing sleeve 67 in the movable grappling arm section 50 and the controlling rod 65 passes through a bearing sleeve 68. The controlling rod 65 also passes through the base block of a handle 69 which is retained in position by means of a washer 70 seated in a groove 71 in the base plate. The washer 70 is secured by means of fastening devices 72 to the gear case 73 which latter is secured to the tank by means of fastening devices 74. The controlling rod 65 is threaded for a portion of its length as at 75 and with this threaded portion cooperates the locking levers 76 having threaded segments to engage the threads 75 of the controlling rod 65. These locking levers 76 are pivotally mounted on the rods 77 carried by the wheel 69 and they are provided with reversely inclined faces 78 with which cooperates the spring pressed stops 79 which hold the locking levers 76 in their locked or unlocked position.

The first movable section 50 of a grappling arm is controlled by a handle wheel 80 fixed to the hub of a gear 81 mounted on the stud shaft 82. The gear 81 meshes with a gear 83 on a shaft 84. The gear 83 meshes with a gear 85 fixed to a gear sleeve 86 which is mounted in the rear end of the support 45 and at its forward end it has fixed to it a gear 87 which meshes with a gear 88 fixed to the inner end of the grapple arm 50. It will thus be seen that when the gear 80 is revolved the movable arm section 50 will be swung on its pivots 52 in one direction or the other. The movable arm section 53 is controlled by the handle wheel 89 which is fixed to the hub of a gear 90 mounted on the hub of the gear 81. The gear 90 meshes with an idler 91 journalled on the stud shaft 84 and this idler 91 meshes with a gear 92 fixed to the bearing sleeve 68. The outer end of the gear 87 is recessed to receive a ball bearing 93 which takes the thrust of a gear 94 fixed to the bear-

ing sleeve 68 and meshing with a gear 95 which meshes with a gear 96 fixed to the bearing sleeve 67. The sleeve 67 at its outer end is provided with a gear 97 which meshes with a gear 98 fixed to the inner end of the second movable grappling arm section 53, so that when the handle wheel 89 is revolved the grappling arm section 53 will be moved on its pivots 54 in one direction or the other.

The rotatable grapple arm support 45 is recessed to receive the gear carrier 86 and a thrust bearing 99 is provided. A sealing washer 100 is interposed as shown in Figure 3 and a threaded gland 101 retains this washer in position. A sealing gasket is also employed as shown at 102 and a gland 103 in threaded engagement with the gear carrier 86 bears against such sealing washer.

In order to retain the controlling members in the position to which they have been adjusted I have provided a locking member for each of them.

The gear 38 controlled by the hand wheel 37 is retained in its locking position by means of the locking member 104 which is provided with gear teeth to interlock with the teeth of the gear 38 and its shank is encircled by a spring 105 which bears against the head of the locking member and the gear casing 73. The shank of the locking member 104 extends through the gear casing and has eccentrically connected with it a handle 106, the rounded eccentric portion of which bears against the gear casing to retain the locking member 104 in its unlocked position. The gear 81 controlled by the hand wheel 80 is secured in locked or unlocked position by means of the locking member 108 constructed and operated in a similar manner to that of the locking member 104 so that a detailed description thereof would involve unnecessary duplication.

In a similar manner the hand wheel 89 is retained in its locked or unlocked position by means of a locking member 109 which has a gear segment interlocking with the teeth of the gear 90.

It will thus be seen that at the will of the operator the grappling rod 65 may be moved inwardly or outwardly to close or open the grappling hooks 36 and it can also be rotated as desired by the hand wheel 69 which is locked thereto by the locking levers 76.

The movable section 50 can be swung on its pivots by rotation of the hand wheel 80 and the outer movable section 53 can be swung on its pivots by rotation of the hand wheel 89. These segments 50 and 53 can also be locked in the position to which they have been adjusted by means of the locking members 108 and 109 respectively.

One of the hooks 36 near its outer end is slotted or bifurcated as at 110 so that the other hook will be received within its slot

and thus form a closed eye to retain any article which has been grasped.

The hydraulic cushioning means is mounted in the wings. These wings are bored out to form the cylinders 5 in which are located the headed plungers 4, the downward position of which is limited by means of the nuts 113, it being understood that the shanks of the plungers extend through the apertures 10 of the nuts 113. The passages 114 lead from the cylinders 5 to the chamber 115 in which is mounted a valve stem 116 which is wing shaped to form apertures 117, the stem carrying the valve 118, which latter is adapted 15 to seat in the valve seat 119 and thus close the inlet passage 120 in the nut 121. The branch conduits 122 are of reduced diameter and lead from the passages 114 through the ports 123 controlled by the outwardly opening valve 124 having a wing shaped stem, so that, the water in the cylinders 111 can slowly escape through the discharge passages 125 when the plungers 4 strike the bottom of a water way. It will thus be seen 20 that I provide an automatic hydraulically actuated cushioning device for the diving tank.

It will now be apparent that in accordance with this invention I have devised a 25 novel diving tank wherein a novel construction and arrangement of grappling arms are provided which enables one to work it any angle in depths of water up to approximately one thousand feet. The telephone connection is within the cable so that it cannot be injured without the breaking of the cable.

The closure is sealed in position and owing 30 to the interrupted threads a quick locking device is provided so that a man can be sealed in or removed from the diving tank in about one minute's time.

All the movable joints of the grappling arms are equipped with thrust bearings to 35 take up the heavy strains to which they are subjected. The revolving stool permits the operator to turn quickly in any direction.

The diving tank is provided with two separate oxygen breathing units which enables one to breath oxygen under atmospheric pressure for a period of eight hours.

The equalizing valve equalizes the pressure in the tank in case of emergency.

I provide both mechanical and automatic shock absorbers to prevent the operator from 45 becoming hurt when the tank reaches the bed of a water way. I provide sixteen unbreakable windows which enables the operator to see in any direction.

I also provide a novel cover locking device 50 so that the grappling hooks will hold on to any object without requiring the use of the hands of the operator. I also provide a quick locking device to hold the grappling arm to any position to which it has been adjusted.

For convenience of illustration I have

shown certain of the gears of the spur type but they would preferably all be spiral gears.

The telephone connection preferably extends through an insulating sleeve 126. The closure disc 27 bears against a packing 127 so that the inner end of the cable connection is effectively sealed.

In order that the cable 17 may be removed when desired the molten metal which is 75 poured in to bind the inner strands in position is received in a casing 128, see Figure 5.

It will now be apparent that I have devised a new and useful diving tank which embodies the features of advantage enumerated as desirable in the statement of the invention and 80 the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages.

Having thus described my invention what 85 I claim as new and desire to secure by Letters Patent, is:—

1. In a diving tank, a tank having a sealed top closure, wings disposed at an angle and depending from the bottom of said tank to 90 form chambers, and hydraulic cushioning means in said wings.

2. In a diving tank, a tank mechanical cushioning means at the bottom of said tank, wings disposed at an angle to each other 100 at the bottom of the tank in which said mechanical cushioning means is mounted, and automatic hydraulic cushioning means at the bottom of said tank.

3. In a diving tank, a tank, a cover sealed therewith and provided with a cored chamber traversed by a rod and communicating with a conically shaped chamber opening through the bottom of the cover, and a cable in said chamber and wound around said rod 110 and sealed in said conically shaped chamber.

4. In a diving tank, a chambered tank, a cover having a quick detachable connection with said tank and sealed thereto, said cover having an annular chamber surrounding a 115 transverse rod opening through the top of the cover and opening into a conical aperture leading through the bottom of the cover, a cable in said chamber surrounding said rod, and having its strands extending into said 120 chamber and separated, and locked therein with melted material, a telephone connection leading through said cable, and a telephone within the tank communicating with 125 said telephone connection.

5. In a diving tank, a tank having wings at its bottom, disposed at right angles to each other and hydraulic cushioning members at the bottom of said tank comprising cylinders mounted in said wings, plungers within said 130

cylinders, inwardly opening automatic inlet valves in communication with said cylinders, and outwardly opening automatic discharge valves in communication with said cylinders.

5 6. In a diving tank, a sectional grappling arm comprising an arm support rotatably mounted on the tank, a section movably connected with said support, a second section movably connected with said first section, 10 grappling hooks mounted for bodily rotation in said second section, a spring actuated rod to which said hooks are operatively connected, independent gear connections for each movable section, controlling means for said gears, a cable connected with said rod, a longitudinally movable controlling rod connected with said cable, a rotatable hand wheel, and means carried by said hand wheel to interlock with said controlling rod.

20 7. In a diving tank, a grappling arm comprising an arm support rotatably mounted on the tank, an arm section movably connected with said support, a second arm section movably connected with said first arm section, grappling hooks mounted for bodily rotation in said second arm section, a longitudinally movable controlling rod operatively connected with said hooks to actuate them, a rotatable hand wheel, locking levers 25 carried thereby to engage said controlling rod, and means to retain said locking members in their locked or unlocked positions.

30 8. In a diving tank, a tank having wings projecting downwardly from its bottom and disposed at right angles to each other, spring 35 pressed plungers carried by said wings, and automatic hydraulic means to form a cushion for said plungers.

35 9. In a diving tank, a tank, a cover sealed therewith and provided with an upwardly 40 extending portion, a packing member sealed with said cover and having a cable receiving aperture, a supporting cable, said cover having an annular passage traversed by a cross 45 rod, said cable passing into said space and around said cross rod, said cover having a cone-shaped chamber communicating with said passage, the free ends of said cable being spread out laterally in said chamber and 50 anchored therein, a closure sealing the lower end of said chamber, a telephone line within said cable, and a socket in said closure connected with said telephone line.

55 10. In a diving tank, a tank adapted to receive an operator, a grappling arm carried by said tank and comprising a support rotatably carried by said tank, a movable section pivotally connected with said support, a second movable section pivotally connected 60 with said first movable section, an arm carrying section rotatably mounted in said second movable section, grappling hooks pivotally mounted supported on said arm sections, a flexible cable connected with said 65 hooks and passing through said movable sec-

tions, yielding means to cause the closing movement of said hooks, a controlling rod connected with said cable and extending into the tank, and a grasping handle for actuating said controlling rod and thereby said 70 grappling hooks.

11. In a diving tank, a tank, a grappling arm comprising a support rotatably mounted in the wall of said tank, a movable section pivotally carried by said rotatable support, 75 a second movable section pivotally carried by said first movable section, an arm section rotatably mounted in said second movable section, grappling hooks carried by said arm section, a cable operatively connected with 80 said grappling hooks and extending through said movable sections, a controlling rod connected with said cable, a bearing sleeve through which said controlling rod passes, and locking means cooperating with said controlling rod to retain it in the position to 85 which it has been adjusted.

12. In a diving tank, a tank, a grappling arm comprising a support rotatably mounted in the wall of the tank, a movable section pivoted to said support, a second movable section pivotally carried by said first movable section, an arm section rotatable in said second movable section, grappling hooks carried by said arm section, a flexible cable connected with said grappling hooks and extending through said movable sections, a controlling rod mounted in said support connected with said flexible cable and having threaded portions, manually actuated locking mechanism cooperating with said threaded portion to retain the grappling hooks in the position to which they have been adjusted, 95 spring pressed stops to retain said locking members in locked or unlocked position, 100 manually actuated means to revolve said support, and manually actuating means to effect relative movement of said sections.

13. In a diving tank, a tank, a grappling arm carried by said tank and comprising a support rotatably mounted in the wall of said tank, a movable section pivotally carried by said support, a second movable section pivotally carried by said first movable section, an arm section rotatably mounted 110 in said second movable section, grappling hooks carried by said arm, a flexible cable connected with said grappling hooks and extending through said sections, a controlling rod loosely mounted in said rotatable support 115 and connected with said flexible cable, locking means cooperating with said controlling rod to retain it in the position to which it has been adjusted by the operator, manually actuated means intergeared with said support to revolve it, locking means for such gearing, manually actuated gearing to effect relative movement of said first movable section and said support, locking means for said last mentioned manually actuated gearing, 125 130

manually actuated gearing for effecting relative movement between said second movable section and said first movable section, and locking means for the gearing for controlling relative movement between said first and second sections.

14. In a diving tank, a tank, a grappling arm comprising a support rotatably mounted in the wall of said tank, a movable section 10 pivotally carried by said support, a second movable section pivotally carried by said first movable section, an arm section rotatably mounted in said second movable section, grappling hooks carried by said 15 arm section, gearing for said support adapted to be manually actuated within the tank to revolve said support and thereby the grappling arm, a cable connected with said grappling hooks to actuate them 20 and extending through said sections, a controlling rod connected with said cable, a bearing sleeve for said controlling rod, a handle connected with said bearing sleeve to revolve it, a gear connected with said bearing sleeve 25 and intergeared with said first movable section to effect relative movement of it with said support, manually controlled gearing intergeared with said second movable section and with said first gearing to effect relative 30 movement of said first and second sections, and locking means carried by said handle and cooperating with said controlling rod to secure it in the position to which it has been 35 adjusted and thereby secure said grappling hooks in the position to which they have been adjusted.
